UNITED STATES PATENT OFFICE.

EDGAR J. BLOOM, OF TIFFIN, OHIO.

OIL-CUP.

1,331,895.

Specification of Letters Patent. Patented Feb. 24, 1920.

Application filed September 8, 1919. Serial No. 322,254.

To all whom it may concern:

Be it known that I, EDGAR J. BLOOM, a citizen of the United States, residing at Tiffin, in the county of Seneca and State 5 of Ohio, have invented certain new and useful Improvements in Oil-Cups, of which the following is a specification.

This invention relates to oil cups and has for its object an oil cup adapted to dependably feed very minute quantities of oil 10 at a relatively slow rate. The cup is arranged to be attached to a moving member, which causes the oil in the reservoir to splash up on the end of the stand pipe, 15 whence it is allowed to feed in minute quantities out of the cup into the bearing.

An improved feature of this cup is that provision is made to very securely anchor the oil collecting upon the end of the stand 20 pipe so that it will stay there and afford a uniform and dependable feed. This will more plainly appear in the specification following.

In the drawings,

25 Figure 1 is a side elevation of the improved cup.

Fig. 2 is a vertical section.

Fig. 3 is a plan view of the barrel of the cup.

30 Fig. 4 is an inverted plan view of the cap.

Fig. 5 is an enlarged fragmentary vertical section showing the correlation between the collector cone of the cap and the end 35 of the stand pipe.

Fig. 6 is a similar view showing a modified form.

a designates the barrel of the cup having its lower end formed into a hexagonal 40 wrench-hold b and an integral extension in the form of a pipe-threaded nipple c. Internally and in alignment with this nipple is a stand pipe d whose upper end is drilled to form a conical basin e. At the bottom 45 of this conical basin is a very small opening approximating 1/70th of an inch and which may properly be called a capillary opening, designated f.

The cap is formed in the regular way except that it is provided with an enlarged 50 central portion forming a cone g, which is an oil collector for the oil that is splashed up on the interior of the cap by the movement of the oil cup. These oil cups are primarily intended to be attached to automobiles or other moving parts. The con-

sequence is the oil is swashed around the cup and dashed against the interior of the cap. This collector cone causes the oil to flow down into the basin e, where it feeds 60 through the capillary opening f into the interior of the stand pipe and thence into the bearing.

A very important feature of this cup is that it employs the principle of air exclusion in restraining the flow through the capillary orifice f. This is accomplished by using the leather or other soft washer h in a seat in the cap between the cone and the cap flange. This engages the top of the 70 barrel when the cap is screwed down and affords a substantially air-tight fit. Inasmuch as the rest of the cup is a single integral piece, no air can enter the cup unless it be through the capillary opening. Obviously this is practically an impossibility as the resistance of the liquid constantly maintained in the basin and in the capillary opening is ordinarily too great to allow the air to pass up through this capillary opening. The walls of the capillary opening and the walls of the basin and cone are so close together that the capillary adhesion of the liquid to these surfaces is sufficiently great to restrain the air pressure forcing 85 air up through this liquid to take the place of liquid dropping down through the capillary opening. This results in a very great resistance to the flow of the liquid through the opening. Consequently it only drops 90 through the liquid opening in single drops at considerable periods but sufficient to afford proper and uniform lubrication to the bearing.

With the cup having no washer h, ordinarily no air-tight fit can be secured here. Hence the air pressure is always behind the oil collecting on the cone and very much facilitates the oil running through the capillary opening. It is a well known fact that 100 an air-tight joint cannot be secured between the ordinary metal to metal contact unless there be a ground joint. Of course, this is out of the question in producing oil cups.

Another improved feature is that the apex 105 of the cone runs down below the rim of the basin. This serves to very securely anchor the oil in the basin from being slopped off the stand pipe by the vibration of the car or other machinery parts. In Fig. 6 110 the apex of the cone is cratered. This provides an additional anchorage for the oil

pillar formed between the end of the cone and the top of the stand-pipe. It is very desirable to have the oil which does collect at this point very securely anchored for obviously if only part of the time it is present, no regularity of flow can be achieved. In fact, the faster an automobile runs and the greater the need of lubricant, the more would the flow be cut down by reason of the violent movement shaking the oil off from the top of the stand-pipe. This anchoring arrangement insures a proper supply of oil for the parts of an automobile even when running at a very high speed.

15 What I claim is:—

1. An oil cup, having in combination, a barrel, a stand-pipe therein provided with a basin in its top having a capillary opening between the bottom of the basin and the interior of the stand-pipe, a cap for the barrel, and a collector member supported over the stand-pipe and having its lower end dipping into the basin below the rim thereof for the purpose of anchoring oil collecting between the basin and the collector from being shaken off from the top of the pipe.
- 20 2. An oil cup, having in combination, a barrel, a stand-pipe therein provided with

a basin in its top with a capillary opening leading from the basin into the interior of the pipe, a cone suspended over the top of the stand-pipe and having its apex dipping into the basin below the rim thereof to form an anchorage for oil collecting at this point, and a closure for said barrel.

25 3. An oil cup, having in combination, a barrel, a stand-pipe therein provided with a depression in its top forming a basin having a capillary opening leading therefrom into the interior of the stand-pipe, and a cap provided with an enlarged central portion forming a collecting cone whose apex dips into the interior of the basin and is below the rim thereof.

4. An oil cup, having in combination, a 45 barrel, a stand-pipe therein provided with a depression in its top forming a basin having a capillary opening leading therefrom into the interior of the stand-pipe, a collecting cone suspended above the stand-pipe and having its apex both cratered and extending below the rim of the basin thereinto, and a closure for the top of the barrel.

50 In testimony whereof I affix my signature.

EDGAR J. BLOOM.
